UNITED STATES PATENT OFFICE.

EDOUARD BELIN, OF PARIS, FRANCE.

PROCESS AND APPARATUS FOR TREATING INKED DOCUMENTS.

Application filed November 20, 1923. Serial No. 675,916.

To all whom it may concern:

Be it known that I, EDOUARD BELIN, a citizen of the Republic of France, residing at Rueil, 272 Avenue de Paris, Seine et 5 Oise, Paris, France, have invented certain new and useful Improvements in Processes and Apparatus for Treating Inked Documents, of which the following is a specification.

10 In order that a written document would be suitable for transmission by telestereographic apparatus, the characters and lines upon it should be formed in clean and hard relief, but on the other hand it is desirable 15 that the ink used should be fluid and capable of drying quickly.

With this object an ink is made by incorporating with ordinary ink sugar or gum in aqueous solution and a highly hygroscopic 20 body, for example about 30 grams sugar and 1 gram of magnesium or calcium chloride or the like in 50 cc. of water.

Such ink is as fluid as ordinary ink and can be used for writing without the special 25 care which is apt to change the characteristic of the writing of the individual which is to be recognized; such ink moreover dries as quickly as any ordinary ink.

The characters are transformed into relief 30 by moistening the ink, sprinkling the document with powdered resin or gum which is retained by the ink, and heating the document up to the melting point of the resin so that on cooling the characters will be 35 lacquered, as it were, in relief. The characters in relief thus produced will be as sharply defined as the original characters, and will not crumble under the exploring points of the telestereographic apparatus so 40 that they can be transmitted with exactitude and be reproduced as autographic writing.

The lacquering should be effected automatically and quickly and always under the same conditions. For this purpose the machine illustrated in the accompanying drawing 45 is employed.

In the drawing:

Figure 1 shows the rehumidification compartment A and the sprinkling compartment 50 B; while Figure 2, which is a continuation of Figure 1, shows the compartment C for removing the superfluous powder and the lacquering compartment D. Figure 3 is a

diagrammatic plan showing one means for controlling the magnet circuit. 55

The documents to be treated are supported in rigid frames which automatically and successively pass through the apparatus from end to end. These frames 35 may be formed of electrical non-conducting material 60 and provided with a conducting surface, as shown in Figure 3, or if preferred the frame may be of conducting material.

A frame is introduced into compartment A through a window or slide 1 and is pushed 65 by hand onto a conveyer band 2 driven by a worm wheel 3 and a worm 4 on a driving shaft 5 which imparts all the necessary movements and which is driven at any desired point by a small motor 6, or in any 70 other suitable manner.

7 is a tray containing water which is heated in any suitable manner, for example by electric resistances 8.

The speed at which band 2 is driven and 75 the degree to which the water is heated are so adjusted that the ink in the document is completely rehumidified and thus recovers its adhesive properties.

Band 2 may be formed of large mesh 80 fabric to allow the free passage of steam which thus completely surrounds the document.

On leaving band 2 the frame enters compartment B, being received by a conveyer 85 band 9. In its passage from one band to the other the frame closes an electric circuit by which an electro magnet 10 is energized so that a pin wheel 11 rotated from a pulley 12 on shaft 5 comes beneath a projection 13 90 on a box 15. Projection 13 will thus be acted on by the pins so long as the frame is upon band 9; the frame on passing out of compartment B breaks the circuit of magnet 10, thus allowing a spring 14 to remove the 95 pin wheel 11 clear of projection 13. The box 15, which is suspended from springs 16 and has a perforated bottom 17, contains pulverized resin or a fusible gum.

The control of the circuit to the electro 100 magnet 10 may be effected by any desired electrical connection, for instance the frame 35 carrying the document may be provided with a contacting strip 36 disposed to be engaged by the circuit contacts 37 when the 105 frame passes onto the conveyer band 9 and

when the frame leaves this band the contacts break the circuit to the magnet.

The shaking of box 15 by the action of the pin wheel causes the powder to be sprinkled over the document and some of the powder will adhere to the moist ink.

The band 9 is driven by means of a wheel 19 meshing with a worm 18 on the shaft 5.

Referring to Figure 2, the sheet is cleaned 10 in compartment C, that is, the superfluous powder is shaken off so that the only powder retained is that which adheres to the ink.

The frame is delivered by band 9 onto a conveyer band 20 which passes over three 15 pulleys 21, 21' and 22 and so takes a very steep path. On the underside of this band are lugs 23 which are subjected to repeated blows from arms 24 mounted on one or more drums 25 also driven by shaft 5.

20 The band 20 is not stretched tight and so the blows against its underside will cause the powder to be shaken off the document. This powder may be collected in a tray at the bottom of compartment C and returned 25 to the box 15.

The document will arrive at the end of compartment C with the still moist ink saturated with powdered resin, but the remaining portions of the document will be 30 free from resin.

The frame now passes from conveyer band 20 onto conveyer band 26 in compartment D for lacquering. Band 26 is driven by a worm wheel 27 rotated from shaft 5 at a 35 suitable speed. Heating is preferably effected electrically by resistances 28 so as to avoid any danger of carbonization; and in order that the heating may be progressive and adjustable the resistance or resistances 40 28 are mounted upon a grid 29 whose angle relatively to the plane of the band 26 may be adjusted by pivoting one end of the grid and moving its other end in a slide by a handle 30. A spring 31 and roller may be used to tension or take up slack in the conveyer band 26.

By altering the angle of the grid and by varying the current in resistance 28 the document may be heated to the exact temperature necessary for lacquering the resin. 50 The document passes out through a door in a completely dry condition with the inked characters in sharp and hard relief.

It is evident that many details are capable 55 of modification without departing from the scope of the invention; in particular the method of driving the conveyer bands, the type of conveyer bands employed, and the heating means employed in the humidification and enameling compartments.

Having now particularly described and ascertained the nature of my said invention and in what manner the same is to be performed, I declare that what I claim is:—

65 1. A process for producing documents

having on them inked characters or lines in hard relief which process consists in producing the character or lines with an ink containing a hygroscopic substance, steaming the document, powdering it with a material capable of forming a lacquer on being heated, shaking the document to remove the powder except from the inked portion, and subjecting the document to heat so as to fuse the powder.

75 2. In a machine for treating written documents, the combination of means for steaming the document, means for sprinkling powder thereon, means for shaking off the superfluous powder, means for heating the document, and means for conveying the document past the various apparatus, substantially as described.

3. In a machine for treating inked documents, a conveyer band, a spring suspended 85 powder box having a perforated bottom, and means for shaking the box during the passage of a document upon said band.

4. A machine according to claim 2, in which the superfluous powder is removed 90 by means of lugs on the rotating arms hitting a conveyer band on which the document is supported.

5. A machine according to claim 2, in which heat is applied to the document by 95 means of electrical resistances carried by a frame which can be adjusted with respect to a band which supports the documents.

6. The process of producing a document 100 for telestereoscopic transmission consisting in effecting an impression thereon with an ink of hydroscopic character, depositing a powdered substance upon the inked surface, removing such substance which does not adhere to the inked lines, and subjecting the powdered lines to a heating medium to solidify the powder.

7. The process of producing a document 110 for telestereoscopic transmission consisting in effecting an impression thereon with an ink of hydroscopic character, subjecting said document to a humidifying action to moisten said ink, depositing a powdered substance upon the inked surface, removing such substance which does not adhere to the inked 115 lines, and subjecting the powdered lines to a heating medium to fuse said powder.

8. In a machine for treating documents, the combination of a humidifying compartment, a powder delivering compartment, a 120 cleansing compartment, a heating compartment, and means for continuously feeding a document successively through the several compartments.

9. In a machine for treating documents, 125 the combination of a humidifying compartment including a steaming pan, means for sifting a powder upon the document moistened thereby, means for removing the excess powder comprising an inclined belt and 130

knocker cooperating therewith, and a heating compartment including a carrier belt and a heating element cooperating therewith.

5 10. In a machine for treating documents, the combination of a humidifying compartment including a steaming pan, means for sifting a powder upon the document mois-

tened thereby, means for removing the excess powder comprising an inclined belt and 10 knocker cooperating therewith, a heating compartment including a carrier belt and a heating element cooperating therewith, and means for adjusting said element relative to the carrier belt.

EDOUARD BELIN.
